UNITED STATES PATENT OFFICE.

JULIUS MARION NELSON, OF TULSA, OKLAHOMA.

FUEL-SUPPLY MEANS FOR INTERNAL-COMBUSTION ENGINES.

Application filed January 7, 1922. Serial No. 527,704.

To all whom it may concern:

Be it known that I, JULIUS M. NELSON, a citizen of the United States, residing at Tulsa, in the county of Tulsa and State of Oklahoma, have invented certain new and useful Improvements in Fuel-Supply Means for Internal-Combustion Engines, of which the following is a specification, reference being had to the accompanying drawings.

10 This invention relates to fuel supply means for internal combustion engines, and an important object of the invention is to provide means for supplying to the engine a dry gas.

15 A further object of the invention is to provide an attachment for internal combustion engines embodying the usual carbureter whereby the carbureter may be employed in starting the engine and subsequently employed to control the mixture fed to the engine, the fuel of the mixture being taken from a separate source.

20 A further object of the invention is to provide a device of this character which is simple in construction and operation and which may be attached to the engine with a minimum change in the construction thereof.

25 Other objects and advantages of the invention will become apparent throughout the course of the following description.

30 In the accompanying drawings wherein for the purpose of illustration is shown a preferred embodiment of my invention and 35 wherein like reference characters designate like parts throughout,

35 Figure 1 is a diagrammatic view showing a fueling system constructed in accordance with my invention;

40 Figure 2 is an enlarged side elevation partially in section, parts being broken away showing the manner of connecting the charge control valve with the throttle operating mechanism of the ordinary carbureter;

45 Figure 3 is a longitudinal sectional view taken through the piston valve showing the piston in the cut off position;

50 Figure 4 is a similar view showing the piston in the open position; and

55 Figure 5 is a fragmentary sectional view of the charge forming device.

Referring now more particularly to the drawings, the numeral 10 indicates the intake manifold of an engine, 11 the usual

carbureter connected with the manifold, 12 the gasoline feed line to the carbureter, 13 the exhaust manifold and 14 the exhaust pipe.

In accordance with my invention I provide a fuel storage tank 15 in the nature of an auxiliary tank and having at the upper side thereof an auxiliary chamber 16 provided with a filler cap 16^a by means of which gasoline may be introduced to the tank 15, the wall of the tank 15 between the auxiliary chamber 16 and the tank proper being perforated, as indicated at 17. At the bottom of the tank 15 a gasoline line 18 is connected having a coil 19 which surrounds the exhaust pipe 14 and which terminates in a lead entering the auxiliary chamber 16 at the top thereof.

70 A second coil 20 is provided of considerable size and open at one end to the air, the other end extending to a point above the level of the gasoline in the tank 15, as indicated at 21. Within the tank 15, at the bottom thereof, a perforated pipe 22 is disposed and this pipe is connected with the coil 20 by a check valve 23 opening toward the tank.

75 The numeral 24 designates a cylinder having one end closed, as indicated at 25, and the other end open, as indicated at 26, the open end of this cylinder being closed by a packing nut 27. In the side walls of the cylinder, at opposed points, are openings 28 receiving nipples 29 and 30. Within the cylinder is arranged a piston valve 31 having an opening 32 adapted to align with the openings 28 when the piston is in one position. The cylinder is of sufficient length to permit shifting of the piston to close communication between the openings 28 when desired. The piston may be operated exteriorly of the casing by means of a stem 33 extending through the packing nut 27.

80 In the use of my invention one of the nipples 29 or 30, for example the nipple 30, is engaged in a prepared opening in the intake manifold 10 and the other of the nipples is connected by a conduit 34 having a valve 34^a therein with the interior of the auxiliary chamber 16. To the throttle lever 35 which is connected with the butterfly valve 37 of the carbureter by the usual link 36 I secure a second link 38 and pivotally connect the free end of this link with the

valve stem 33 of the piston valve. This connection is made in such a manner that the piston valve moves a relatively small distance in comparison with the movement 5 of the butterfly arm of the carburetor, the adjustment being such that the piston valve is completely closed when the carburetor is completely closed and completely open when the carburetor is completely open.

10 In the operation of the device the engine is first started and run with the valve 34^a in the line 34 closed. After the engine is heated up the control valve 12^a in the gasoline line 12 to the carburetor is closed and 15 the valve 34^a opened. The gasoline in the carburetor becoming exhausted, the entire gas supply is drawn from the chamber 16. Since the air drawn through the conduit 34 has been preheated by its passage around 20 the exhaust pipe and since heated gasoline vapors are present in the chamber 16 due to the arrangement of the coil about the exhaust pipe, a substantially dry gas which is very rich will be drawn into the intake manifold through the piston valve. Since 25 the piston valve is opened in proportion to the throttle valve of the carburetor, an ideal mixture, in so far as is possible without the use of complicated adjustments, is drawn 30 into the engine. When the throttle is nearly closed the vacuum created within the intake manifold is much higher and a larger quantity of gas is drawn from the chamber 16 enriching the mixture. As the throttle 35 is opened and speed increased, the vacuum lessens and less gas is drawn into the intake manifold giving a lean mixture. Since this gas is very dry and to a great degree free 40 from moist particles, the loss in efficiency in the engine due to dilution is lessened and the likelihood of the formation of carbon is likewise lessened. Furthermore, a dry charge explodes much more completely than the ordinary saturated charge drawn from 45 the carburetor affording a large percentage of pure loss. In order to prevent back fir-

ing of the engine through the conduit 34, a check valve 39 may be employed which opens toward the intake manifold 10.

From the foregoing it is believed to be 50 obvious that my fuel supply system may be readily attached to any of the standard makes of engines without materially altering the construction thereof and that the device when attached will increase the efficiency of the engine and effect a saving in the use of both fuel and oil. It will furthermore be obvious that many changes are possible in the shape, size and arrangement 55 of the various parts herein shown without in any manner departing from the spirit of my invention and I accordingly do not limit myself to the specific structure thereof, except as hereinafter claimed.

65 I claim:

1. The method of fueling internal combustion engines consisting in employing the usual carburetor and intake manifold and in addition employing means for forming a highly charged fuel gas, starting the engine employing the charge formed by the carburetor, cutting off the supply of fuel to the carburetor, admitting the fuel gas directly to the manifold and controlling the supply of air for admixture with said fuel 70 gas by the throttle valve of the carburetor. 75

2. The method of fueling internal combustion engines consisting in employing the usual carburetor and intake manifold and in addition employing means rendered operative by the operation of the engine for forming a highly charged fuel gas, starting the engine employing the charge formed by the carburetor, cutting off the supply of fuel to the carburetor, admitting the fuel gas directly to the manifold and controlling the supply of air for admixture with said fuel gas by the throttle valve of the carburetor. 80 85

85 In testimony whereof I hereunto affix my signature.

JULIUS MARION NELSON.
